No. 653,571.

Patented July 10, 1900.

J. P. FARMER.

GAS BURNER.

(Application filed July 17, 1899.)

(No Model.)

UNITED STATES PATENT OFFICE.

JOHN P. FARMER, OF PORTLAND, OREGON.

GAS-BURNER.

SPECIFICATION forming part of Letters Patent No. 653,571, dated July 10, 1900.

Application filed July 17, 1899. Serial No. 724,126. (No model.)

To all whom it may concern:

Be it known that I, JOHN P. FARMER, a citizen of the United States, residing at Portland, in the county of Multnomah and State of Oregon, have invented a new and useful Gas-Burner, of which the following is a specification.

This invention relates to gas-burners, and more particularly to that class known as "safety" gas-burners; and it has for its object to provide a device of this nature including a thermostatic cut-off valve which may be operated to open and hold open the gas-passage to the main burner and which also will operate to close the supply of gas to the main burner at a predetermined time after the extinguishing of the flame of the main burner.

The invention consists of a valve and a valve-casing, the valve-casing comprising two channels leading from one side of the valve and one of which communicates with a tubular extension, concentric with which and inclosed thereby is a main burner-tube having communication with the other gas-passages and which latter is controlled by a separate opening in the valve. As the valve is turned it opens first the main supply and afterward the supplemental supply to the space between the main burner-tube and the inclosing tubular extension. At this time the main burner-opening is closed, because of the contraction of the material of the main burner-tube, to draw a valve-seat carried thereby into operative connection with an adjacent fixed valve-stem. The valve is held in this position to permit the escape of gas from the tubular extension which forms the pilot-burner, which gas is then ignited, and the heat thereof acts to expand the main burner-tube to unseat the valve therein. The gas then passes through the main burner and is ignited from the pilot-burner. The valve is then released and is returned by a suitably-disposed spring to a position to aline the main burner-passage with its corresponding opening in the valve.

In the drawings forming a portion of this specification, and in which like numerals of reference designate corresponding parts in the several views, Figure 1 is a side elevation showing the burner complete. Fig. 2 is a vertical section of the burner. Fig. 3 is a sec-

tion on line 3 3 of Fig. 2. Fig. 4 is a detail section of a second form of main burner. Fig. 5 is a detail section of a third form of main burner. Fig. 6 is a section on line 6 6 of Fig. 2.

Referring now to the drawings, 5 represents a casing, transversely and vertically of which is journaled a tapered valve-plug 6, adjacent one end of which is formed a passage 7, adapted to aline at times with what is termed a "pilot-passage" 8, which is adapted to convey gas from the passage 7 to the pilot-burner formed by the upper end of a vertical tubular extension 9 at the end of the casing 5.

Below the passage 8 is a second and larger passage 10, adapted to communicate at times with a passage 11, formed through the plug 6 and adapted to convey gas from the rear portion of the casing 5 forwardly thereof. In the upper wall of the passage 10 and in axial alinement with the tubular extension 9 is a threaded perforation 12, with which is engaged the lower threaded end of a main burner-tube 13, passing upwardly through and concentric with the extension 9 and projecting thereabove. This tube 12 is of brass or other metal having a high coefficient of expansion, and upon the upper screw-threaded end thereof is arranged a metallic tip 14, having an interior valve-seat 15, adapted for engagement by a valve formed by the upper end of a rod 16, of steel or similar material of low expansibility. This rod 16 passes downwardly and centrally of the tube 13 and has threaded engagement with a perforation in the lower wall of the passage 10. Normally the separation between the said valve and its seat is equal or approximately equal to the expansion of the burner-tube under the influence of the normal temperature incident to a flame of the usual size at the main burner. Thus if the flame be extinguished the burner-tube will be contracted to seat the valve in the seat, and thus will prevent the flow of gas through the burner.

In practice the plug 6 is rotated to the position shown in Fig. 2 of the drawings, when the passage 7 will aline with the passage 8 and the passage 11 will partially aline with the passage 10. At this time the main burner-tube will be closed against the passage of gas therethrough, while there will be an

escape of gas from the top of the extension 9, which forms the pilot-burner. If this gas be then ignited, it will act to heat the main burner-tube to expand it and move the seat 5 away from the valve. The main burner-tip 14 and passage 10 will then be opened to the supply of gas, with which the valve-casing is connected, and which gas will pass upwardly through the main burner and will be 10 ignited by the flame of the pilot-burner. The flame at the main burner will then act to maintain a sufficient temperature of the burner-tube to prevent its contraction and to hold the valve open and secure a continuous 15 supply of gas and a continuous flame.

As soon as the main burner or the gas therefrom is ignited by the flame of the pilot-burner it is desirable to cut off the flow of gas through the pilot-burner, and to insure 20 this action automatically the plug 6 is provided with a lug 20, extending radially thereof and bearing at its outer end upon the spring 21, seated in a recess 22 in the valve-casing and so positioned that when the plug 25 lies to fully aline the passages 10 and 11 the lug contacts with the end of said spring, and when the lug is moved to cause alinement of the passages 7 and 8 it moves against the tendency of the spring and compresses it. 30 Thus when this alinement of passages 7 and 8 is no longer required—that is, after the main burner-tube has become sufficiently heated and the gas of the main burner is ignited—it is only necessary to release the plug 35 6, when the spring 21 is rotated sufficiently to move the passage 7 from alinement with the passage 8 and to aline the passages 10 and 11. The spring 21 is of such a length and has such a position that when the plug 6 is 40 in a position to close both passages the lug 20 is out of engagement with the end of the spring 21, and this lug does not engage the spring until the plug has been rotated sufficiently far to aline the passages 10 and 11. 45 Therefore when the plug is moved to destroy the alinement of the passages 7 and 8 and to aline the passages 10 and 11 said plug will retain this position until rotated to cut off the supply of gas to the main burner or to 50 give a fresh supply to the pilot-burner in the event of the main-burner flame being extinguished.

In Fig. 4 of the drawings there is shown a different construction of main burner, in 55 which the tip has its lower portion exteriorly threaded and engaging threads on the inner surface of the end of the main burner-tube.

In Fig. 5 of the drawings is shown a construction in which the tip and tube are integral, it being of course understood that any other specific construction of tube may be used.

The threaded engagement of the valve-stem enables the adjustment of the valve with respect to the seat, while in the employment of

a separable tip an additional means of adjustment for this purpose is provided.

It will be further understood that various changes in the specific construction and arrangement shown may be made and that any suitable material may be employed for the various parts without departing from the spirit of the invention.

Having thus described the invention, what is claimed is—

1. In a gas-burner, the combination with a casing having a tubular extension, of a burner-tube arranged concentric with the extension and formed of thermostatic material, a valve-seat carried by the burner-tube, a valve for 80 said seat, a gas-passage through the casing and communicating with the burner-tube, a separate gas-passage formed through the casing and communicating with the interspace between the burner-tube and the extension 85 of the casing, a turning plug in the casing and having separate passages adapted to communicate with the passages of the casing, the passages of the plug lying at an angle to each other, whereby one of said passages may lie 90 out of register with its casing-passage, while the other plug-passage is in register with its casing-passage, and a spring adapted for initial engagement by the burner-plug when the burner-tube passage is opened and to be compressed when the plug is moved to open the passage to the interspace, whereby said spring will permit the plug to lie with the burner-tube open and will return the plug to close the passage to the interspace when the plug 95 is released.

2. In a gas-burner, the combination with a main burner and a pilot-burner having separate gas-passages leading thereto, of a turn-plug having passages adapted to register with 105 their respective first-named passages, the passages of the plug lying at an angle to each other, whereby one of said plug-passages may lie out of register with its burner-passage while the other plug-passage is in register 110 with its respective burner-passage, and whereby both plug-passages may communicate with the burner-passages simultaneously, and a spring adapted for initial engagement by the plug when one of its passages is in 115 register with its burner-passage and to be compressed when the plug is rotated to cause communication of the plug-passages simultaneously with the burner-passages, whereby the plug will be returned to register one of 120 the passages with its burner-passage and may lie in this position.

In testimony that I claim the foregoing as my own I have hereto affixed my signature in the presence of two witnesses.

JOHN P. FARMER.
